UNITED STATES PATENT OFFICE.

COLLUMBUS PHILLIPS, OF ATLANTA, GEORGIA, ASSIGNOR OF TWO-THIRDS
TO GREEN I. FOREACRE AND JOSEPH B. TRAVIS, BOTH OF SAME PLACE.

STEAM AND AIR BRAKE.

SPECIFICATION forming part of Letters Patent No. 307,492, dated November 4, 1884.

Application filed February 12, 1884. (No model.)

To all whom it may concern:

Be it known that I, COLLUMBUS PHILLIPS, a citizen of the United States, residing at Atlanta, in the county of Fulton and State of 5 Georgia, have invented certain new and useful Improvements in Steam and Air Brakes; and I do hereby declare the following to be a full, clear, and exact description of the invention, such as will enable others skilled in the 10 art to which it appertains to make and use the same.

My invention relates to atmospheric air-brakes used on railways, and has for its object to effectually prevent the sticking of the 15 piston in the brake-cylinder when the brakes are taken off, and consequently the necessity of "bleeding" the brake-cylinder, as heretofore, to effect the release of the piston; and to that end it consists in completely, so far as 20 effecting the release is concerned, exhausting the air from the said cylinder at the time that the brakes are taken off by means under the control of the engineer without leaving his cab, of which an illustration will be given in 25 the accompanying drawings, and particularly described in the following description.

In the drawings, Figure 1 is a perspective of the auxiliary reservoir (broken in two) 30 brake-cylinder and triple valve of a Westinghouse air-brake with my attachment applied thereto, some of the parts being in section. Fig. 2 is an enlarged view in elevation of my release attachment in vertical section. Fig. 3 is a plan view on the line $x-x$ of Fig. 2; 35 Fig. 4, a bottom view of valve in the brake-release chamber.

In the accompanying drawings, the letter A indicates the main brake-pipe connected by a branch pipe, B, with the triple valve C, formed 40 with two chambers, D and E, in which work the piston F and stem G, and slide valve H, the casing or shell I of the triple valve being formed, in addition to the port for the main brake-pipe, with the port J for the auxiliary 45 reservoir K, and the port L for the pipe M leading to the brake-cylinder N; also, with the four-way cock O, and other usual features, as illustrated, of the triple valve in general use in the Westinghouse air-brake. These

parts, so far generally referred to, are of well-known construction, and operate in the usual well-known way, and therefore need not be more particularly described.

Under the construction referred to, while the air is exhausted from the brake-cylinder to release the brakes, still, at times from the air not being completely exhausted, the brake will stick, and it then becomes necessary to go to the cylinder and turn a cock, so as to "bleed" the cylinder before the brake will 55 release. The inconvenience and disadvantages attending such necessary steps are familiar to all locomotive-engineers. Various means have been devised to overcome such difficulties. In order to overcome such 60 inconveniences and difficulties, I connect with the brake-cylinder and the main brake-pipe an attachment constructed as follows: Two 65 chambers, P and Q, which I will designate, respectively, as the "air-pressure chamber" 70 and the "air or brake release chamber," are connected together by a bar, R. The air-pressure chamber is provided with upper and lower screw-caps, P' P'', and within it is fitted a valve, P³, the stem P⁴ of which passes through 75 the upper cap, while to its lower face a leather cup-valve, P⁵, is secured by means of the plate or washer b and screw c. A suitable 80 spring, preferably a coiled spring, P⁶, fits between the upper cap and top face of valve P³, and exerts a downward pressure on the valve 85 when compressed. The air-release chamber Q is preferably of smaller diameter than the pressure-chamber, and is provided with upper and lower caps, Q' Q'', which preferably 90 screw into the chamber, the upper cap having a valve-seat, d, formed therein. Within the release-chamber is fitted a valve, Q³, of any construction suitable for the purpose, but preferably of the form shown with wings e, 95 and having notches or ports f made in its periphery for the passage of steam when the valve is unseated, and with its stem Q⁴, which passes through the upper cap, slightly flattened, as seen at i, on one or more sides for the whole or a portion of its length, to permit 95 the escape of steam between the stem and the walls of the opening in the cap when the valve

is unseated. A suitable spring, Q⁵, preferably a spiral spring, fits between the lower cap and the valve and bears against both, so that it will hold the valve against its seat and assist 5 in reseating it after the pressure which unseated it has been reduced or overcome. Normally the stems of both valves preferably 10 protrude outside of their respective chambers, and bear against or are in such proximity thereto 15 that they can be readily brought into contact with a beam, R', pivoted or journaled by a pin or bolt, g, to a post or support, R², connected by a bolt, h, or other suitable means to the bar R. This beam-lever preferably stands 20 at an inclination, as shown, with its longest arm between its support and the pressure-chamber; but if necessary it can be adjusted to bring the longest arm between the release-chamber and post, both the beam and connecting-bar being formed with a series of holes 25 for the adjustment of both beam and post, or either.

The attachment constructed as described is applied by connecting the pressure-chamber P 25 with the main brake-pipe by means of a pipe, S, entering the coupling A' at one end, and the lower cap of the pressure-chamber at the other end, and the release-chamber with the brake-cylinder by means of a pipe, T, entering the 30 lower cap of the pressure-chamber and connecting with the cock U, heretofore used for bleeding the brake-cylinder. It will be thus observed that the attachment can be applied to brakes already in use very readily and at a 35 very small cost.

In operation, when the engineer from his cab exhausts the air from the main brake-pipe to 40 put on the brakes, and the air passes from the auxiliary reservoir to the brake-cylinder through the connecting-pipe, the air at the time that it enters the brake-cylinder also passes from the same through pipe T into the release-chamber and presses against the valve 45 therein, but cannot escape, because the valve is pressed against its seat, and hence the brake is applied as effectively as heretofore; but when the pressure is applied through the main pipe as heretofore to release the brakes, a sufficient portion of the air passes through pipe 50 S into the pressure-chamber P to overcome the spring therein and press out the valve-stem so that it will bear against and elevate that end of the beam, thereby lowering the other end, and through it pressing down the 55 stem and unseating the valve in the release-chamber, so as to effect an escape for the steam from the brake-cylinder through the release-chamber, and hence so long as the valve in the release-chamber is open and the pressure 60 in the brake-cylinder is greater than the atmospheric pressure the air must escape from the cylinder, and consequently there can be no possibility of the piston sticking by reason of pressure of air in the cylinder preventing 65 it from receding to its former position. It will be observed, too, that the operation of the

release is under the absolute control of the engineer from the cab, and that the piston cannot stick, and that the necessity of bleeding the brake-cylinder as heretofore in the construction of air-brakes such as described is completely overcome.

The capacity of the two chambers and the tension of the springs and the leverage of the beams are such that when air is applied to 70 take off the brakes the pressure of the air admitted to the pressure-chamber will easily overcome the pressure of the springs and of the air in the brake-cylinder.

I have, for the purposes of illustration and 80 of showing how the releaser can be applied to the Westinghouse brake in common use, shown the releaser applied to such a brake with its ordinary appendages; but it will be understood that I do not limit myself to its use with 85 the details of construction of the several parts of such a brake, as changes may be made in such parts, and my invention still be serviceable for the purpose for which it was designed.

I have described the parts as applied to air-brakes; but it will of course be understood that the invention is not limited to such use 90 where it can be used with other motive power.

Having thus described my invention and set forth its merits, what I claim is—

1. The combination, with the brake-cylinder and main brake-pipe, of a pressure-chamber communicating with the main pipe to receive air therefrom, a release-chamber communicating with the brake-cylinder, valves 100 within the two chambers, and means for transmitting motion from one valve to the other, to unseat the latter and allow the exhaust of air from the brake-cylinder, substantially as set forth.

2. The combination, with the brake-cylinder and main brake-pipe, of a pressure-chamber communicating with the main pipe to receive air therefrom, a release-chamber communicating with the brake-cylinder, valves 110 within the two chambers, and a beam for transmitting motion from one valve to the other, to unseat the latter and allow the exhaust of air from the brake-cylinder, substantially as set forth.

3. The combination, with the brake-cylinder and main brake-pipe, of a pressure-chamber communicating with the main pipe to receive air therefrom, a release-chamber communicating with the brake-cylinder, valves 120 within the two chambers, springs acting on said valves to restore them to their normal positions after movement therefrom, and a beam for transmitting motion from one valve to the other, to unseat the latter and allow air to exhaust from the brake-cylinder, substantially as set forth.

4. The combination, with the main brake-pipe, the brake-cylinder, and means for controlling the passage of air from the main pipe 130 to the brake-cylinder, of a pressure-chamber communicating with the brake-cylinder, valves

within the two chambers, and means for transmitting motion from one valve to the other, to unseat the latter and allow the exhaust of air from the brake-cylinder, substantially as set forth.

5. The combination, with the main brake-pipe, the auxiliary reservoir, the brake-cylinder, and means for controlling the passage of air from the main pipe to the auxiliary reservoir, and thence to the brake-cylinder, of a pressure-chamber communicating with the main pipe, a release-chamber communicating with the brake-cylinder, valves within the two chambers, and means for transmitting motion from one valve to the other, to unseat the latter and allow air to exhaust from the brake-cylinder, substantially as set forth.

6. The combination of the release-chamber provided with a valve and escape-port, and constructed to receive air from the brake-cylinder, and a pressure-chamber provided with a valve connected with the valve in the release-chamber, and constructed to receive an inflowing agent to actuate its valve to transmit its movement to the valve in the release-chamber, to unseat the same to open the escape-port, substantially as and for the purpose set forth.

7. The combination of the pressure-chamber provided with the valve having a stem sliding through the end of the chamber, the release-chamber connected to the pressure-chamber

without communicating therewith, and provided with the valve having a stem sliding through the end of the chamber, and the beam 35 fulcrumed upon a suitable support and connecting the stems of the two valves, substantially as set forth.

8. The combination of the pressure-chamber and release-chamber, each provided with the 40 detachable caps, the valve to each chamber provided with a stem passing through the end of the chamber, and the cross-beam fulcrumed on a suitable support, and having its opposite ends over the ends of the valve-stems, and 45 adapted to receive momentum therefrom, substantially as set forth.

9. The combination of the pressure-chamber, the release-chamber, the valves within the two chambers having stems sliding through the 50 ends of the chambers, the springs acting on the valves, and the beam connecting the stems of the valves, substantially as set forth.

10. The combination, with the pressure-chamber and the release-chamber and their 55 valves, of the adjustable post or support, and the beam adapted to be adjusted on said post or support, substantially as set forth.

In testimony whereof I affix my signature in presence of two witnesses.
